UNITED STATES PATENT OFFICE.

JOHN S. BRENNAN, OF MILWAUKEE, WISCONSIN.

FUEL-RESERVOIR.

1,343,343.

Specification of Letters Patent. Patented June 15, 1920.

Application filed December 16, 1919. Serial No. 345,167.

To all whom it may concern:

Be it known that I, JOHN S. BRENNAN, a citizen of the United States, and resident of Milwaukee, in the county of Milwaukee, 5 and State of Wisconsin, have invented certain new and useful Improvements in Fuel Reservoirs; and I do hereby declare that the following is a full, clear, and exact description thereof.

10 My invention relates to new and useful improvements in reservoirs adapted for use on oil stoves and of that type including a main supply receptacle detachably mounted in inverted position over an auxiliary 15 constant level receptacle, the mouth of the main receptacle being provided with a valve opened by a stem engageable with the bottom of the auxiliary receptacle whereby a constant level of fluid is maintained in 20 the auxiliary receptacle, said level being determined by the bottom of the mouth or discharge neck of the main receptacle which projects thereto, said valve member closing upon lifting the main receptacle from 25 the auxiliary receptacle to prevent spilling of the oil in manipulating the main receptacle for the purpose of replenishment.

It is the object of my invention to increase the strength and the firmness of support afforded to the main detachable receptacle by the auxiliary receptacle having the usual rigid connection with the stove structure, and to increase the efficiency of devices of this character particularly with respect to insuring the provision and maintenance of a proper fluid level in the auxiliary receptacle for coöperation with the burner members of the stove.

My present structure is intended for use 40 in connection with burner members whose burning action is controlled by raising or lowering them with respect to the constant level fluid line and in view of the mechanical connections in procuring movement of 45 the burners it is highly important that the constant fuel level lie in a predetermined plane with respect to said mechanism.

In view of the fact that the glass bottles employed to form the main supply receptacles of stoves are provided with necks of varying length, and have heretofore been supported by seating of their shoulder portions in definite relation to the auxiliary receptacle, the constant level line has heretofore varied in accordance with variation 55 of the length of the bottle necks. It is

therefore particularly my object to provide a support means for the main receptacle wherein the vertical support is afforded by means having definite relation to the end of the bottle necks so that a constant level of fluid would be maintained in the auxiliary receptacle irrespective of variation of lengths of the bottle necks.

With the above and other objects and advantages in view, which will be apparent as the description proceeds, my invention resides in the novel features of construction, combination and arrangement of the parts as hereinafter described and defined by the appended claims.

In the accompanying drawing:

The figure shows a vertical sectional view through my improved reservoir and control valve structure.

Referring now more particularly to the drawing 5 designates the usual pan shaped auxiliary receptacle of an oil stove having the supply pipe 6 depending from its bottom at one side and in the present instance 80 a plurality of upstanding arms 7 are secured to the wall of the auxiliary receptacle 5 and are connected at their upper ends by a band 8 which slidably receives and forms a lateral support for the main 85 receptacle 9, which comprises as usual a glass bottle having a valve cap 10 threaded on its neck. It will, however, be appreciated that the wall of the auxiliary receptacle 5 may be extended upwardly to form 90 a lateral support for the body of the main receptacle 9 and the band 8 may consequently be termed an extended portion of the auxiliary receptacle, the essential feature of support, novel in the present instance, being that the end shoulder of the bottle is not afforded a seat.

As shown in my co-pending application for patent filed Oct. 6, 1919, Serial No. 328,796, the valve structure carried by the 100 cap 10 comprises an inner valve casing section 11 secured within the cap about an outlet port formed by a central aperture in the bottom portion of the cap, the cap material adjacent said aperture being inclined 105 to form a frusto-conical seat for coöperation with the flared upper end of a tubular valve member 12 passed through the cap aperture, said tubular member being closed at its outer end and resiliently urged outwardly by a spring 13 disposed therein and bearing against said closed outer end and

against the casing portion 11. The outer portion of the tubular valve stem 12 is slidably passed through a bearing plate 14 which is spaced from and connected with the 5 end of the cap by the arms 15. Thus when the main receptacle is inverted over and lowered to engage its neck portion into the auxiliary receptacle 5, the stem of the valve member 12 will engage the bottom of the 10 auxiliary receptacle and will hence become disengaged from its seat on the cap member, thus permitting oil to flow freely from the main receptacle into the auxiliary receptacle, to a constant level line which is 15 determined by the end of the cap 10 threaded on the bottle neck.

To insure that possible variation of the length of the bottle neck will not effect the desired plane of the constant level, I associate the vertical support means for the main receptacle with the cap 10 and thus in the 20 present instance I provide a plurality of divergent legs 16 on the cap member which seat on the bottom of the auxiliary receptacle. It is, however, noted that the upper end of the valve member is afforded a seat in its open position by a shoulder portion 17 of the casing member 11, and thus the 25 valve member also forms a vertical support for the receptacle, and I may utilize this seating of the valve member in its open 30 position as the sole support.

I have thus provided an exceedingly simple structure for mounting a main fuel supply receptacle in such manner that variation 35 in size of portions of the receptacle will not interfere with the procurement of a desired constant level fuel line when the receptacle, which would be formed of glass, is associated with the more accurately proportioned metallic parts of the stove structure, and it will be noted that a firm and more 40 positive vertical support is afforded in the present instance in contra-distinction to supports engaging intermediate or shoulder 45 portions of the main receptacle.

While I have shown and described a preferred embodiment of my invention, it will be appreciated that various changes and 50 modifications of structure may be employed to meet differing conditions of use and manufacture, without departing in any manner from the spirit of my invention.

What is claimed is:

55 1. In a constant level fuel supply struc-

ture, an auxiliary receptacle, a main receptacle having its neck portion engaged in the auxiliary receptacle, means for supporting the main receptacle against lateral movement and means associated with the bottle 60 neck and engaging the auxiliary receptacle to provide a vertical support for the main receptacle.

2. In a constant level fuel supply structure, an auxiliary receptacle, a main receptacle 65 having its neck portion engaged in the auxiliary receptacle, means for supporting the main receptacle against lateral movement, a valve cap secured on the neck of the main receptacle and vertical support means for 70 the main receptacle carried by said cap.

3. In a constant level fuel supply structure, an auxiliary receptacle, a main receptacle having its neck portion engaged in the auxiliary receptacle, means for supporting 75 the main receptacle against lateral movement, a valve cap secured on the neck of the main receptacle, a valve structure carried by the cap and including a movable valve member having a stem engageable 80 with the bottom of the auxiliary receptacle to open the valve, said valve member being adapted to seat in the valve structure in open position whereby said stem affords a vertical support for the main receptacle, 85 and said lateral support means for the main receptacle permitting vertical movement of the main receptacle to procure said seating engagement of the valve member.

4. In a constant level fuel supply structure, an auxiliary receptacle, a main receptacle having its neck portion engaged in the auxiliary receptacle, a valve cap secured on the neck of the main receptacle, an apertured bearing member carried by the cap 90 in spaced relation thereto, valve mechanism carried by the cap for controlling flow of fluid therethrough and including a stem 95 slidale in said bearing member, said stem being adapted to afford vertical support for 100 the main receptacle and means for supporting the main receptacle against lateral movement, said means permitting vertical movement of the main receptacle to effect its vertical support by the stem.

In testimony that I claim the foregoing I have hereunto set my hand at Milwaukee, in the county of Milwaukee and State of Wisconsin.

JOHN S. BRENNAN.
